UNITED STATES PATENT OFFICE.

HENRY C. SWAN, OF OSHKOSH, WISCONSIN.

DESIGN FOR A LOWER FIFTH-WHEEL.

SPECIFICATION forming part of Design No. 32,927, dated July 10, 1900.

Application filed May 12, 1900. Serial No. 16,521. Term of patent 14 years.

To all whom it may concern:

Be it known that I, HENRY C. SWAN, a citizen of the United States of America, residing at Oshkosh, Winnebago county, State of Wisconsin, have invented and produced a new and original Design for Lower Fifth-Wheels, of which the following is a specification.

In the accompanying drawings, Figure 1 is a plan view of a lower fifth-wheel, showing my new design. Fig. 2 is a vertical section of the same on the line 2 2 of Fig. 1. Fig. 3 is a front elevation of the same, the lower fifth-wheel circle being shown in section on the line 3 3 of Fig. 1.

As shown in the drawings, the leading or material feature of my design consists in a new and novel configuration for a lower fifth-

wheel. The braces 1 extend between the ends of the flanges 2 upon the sleeve or collar 3 and the lower fifth-wheel circle 4. The braces are 20 curved downward and inward from the fifth-wheel circle to connect with the ends of the flanges.

What I claim as new, and desire to secure by Letters Patent, is—

The design for a lower fifth-wheel herein shown and described.

In testimony whereof I sign this application, in the presence of two witnesses, this 5th day of May, 1900.

HENRY C. SWAN.

Witnesses:

S. D. SANOR,
C. I. HENDERSON.
